GUM WRAPPING MACHINE

Albert Kneaskern, Canajoharie, N. Y., assignor
to Beech-Nut Packing Company, Canajoharie,
N. Y., a corporation of New York

Application March 15, 1932, Serial No. 598,927

11 Claims.

(Cl. 93—2)

My invention relates to wrapping machines, and has special reference to gum wrapping machines in which individual sticks or pieces of gum are first wrapped in paper-lined foil, a paper label is placed around the foil wrapper with its edges overlapping and glued together, then the individual pieces are stacked in groups, usually of five, and the groups or stacks are then enclosed by a paper label to complete the package.

In gum wrapping machines of this type, it has heretofore been a serious problem to stack the individual pieces after the labels have been applied without more or less opening up or otherwise deranging the newly pasted overlapping seam of the labels. Such derangement of the seam is likely to result in crumpling and loosening the label and paper-lined foil wrapper and jamming the gum during the stacking and subsequent operations so that the completed package is liable to have one or more of the wrapped pieces of gum in a distorted or defective condition, thus effecting the appearance of the package as a whole, and preventing the proper application of the label that encloses the several stacked pieces.

The principal object of the present invention is to provide novel and improved means for stacking the individual sticks or pieces of gum after the labels have been applied which overcomes the disadvantages above described of the prior constructions.

Another object of the invention is to provide a novel and improved wrapping machine of the character indicated.

The several features of the invention, whereby these and other objects may be attained, will be readily understood from the following description and accompanying drawings, in which:

Figure 1 is a side view of a portion of a gum wrapping machine embodying the features of my invention in their preferred form;

Fig. 2 is a sectional view taken on the line 2—2 of Fig. 1;

Fig. 3 is a plan view of the portion of the machine illustrated in Fig. 1; and

Figs. 4 and 5 are views corresponding to a portion of Fig. 1 but showing certain parts in different positions.

The machine illustrated in the drawings is provided with a rotary tumbling barrel or wrapping head 2 having slots 4 for receiving the individual pieces of gum that have been wrapped in paper-lined foil, the mechanism for wrapping the pieces in paper-lined foil not being shown. The individual pieces of gum carry the labels to be applied

thereto with them into the slots 4 so that the label is positioned over the inner edge and the two sides of the gum with one edge portion 6 of the label projecting a distance beyond the outer edge of the gum. During the rotation of the drum this projecting portion 6 of the label by engagement with a curved guiding surface 8 on a table 10 is bent over the outer edge of the gum, and as each piece of gum reaches the plane of the table, it is ejected from the slot and fed over the table. As the piece of gum is thus fed edgewise over the table, the projecting edge 6 of the label is brought up into overlapping engagement with the other edge of the label, adhesive previously applied securing the edges together.

The pieces of gum are fed in spaced relation beneath a guide-bar 12 to a definite position or station in front of said guide bar, any suitable devices being provided for thus feeding the gum, such as the members 14, these members also serving to eject the pieces from the wrapping head and upon the table as above described. The table 10 is made up of longitudinally extending rails 16, there being three such rails which are spaced apart as shown.

The parts of the machine above referred to may be and preferably are of a well known construction.

In accordance with the present invention, novel and improved means are provided for stacking the individual pieces of gum in groups of five pieces as they are delivered to the station in front of the guide bar 12, as above described. As shown, the table 10 is provided with an upwardly opening transverse recess or slot 18 which extends across the three rails of the table and is of slightly greater width than the width of the pieces of gum. The top of the table has an upward projection forming an abutment 19 which forms an extension of the rear wall of the slot 18. A horizontal support 20 is mounted to slide vertically in said slot 18. This support comprises a bar which is secured upon the upper end of a rod 22 that is mounted to slide in a vertical aperture which extends through the bottom wall of the slotted portion of the central rail of the table 10. The lower end of this rod is secured to a yoke 24 which embraces and is mounted to slide on a block 26 that is loosely mounted on a rotating shaft 28. The yoke 24 carries a cam roll 30 which is held in engagement with a cam 32 secured on the end of the shaft 28, by means of a coiled spring 34 interposed between the upper side of the block 26 and the lower end of the rod 22. The shaft 28 is

suitably journaled in bearings 36 on the machine frame and is driven through a gear 38 secured thereon, which is operatively engaged by a pinion 40 secured on a drive shaft 42.

5 Above the slot 18 and plunger 20 there are 10 guide rolls 44 which are carried on the ends of arms 46 secured to a shaft 48 mounted for 15 pivotal movement in bearings in the guide bar 12. The rolls 44 are pressed downwardly a limited 20 distance by means of a spring 50 coiled about the shaft 48 and having one end secured to the shaft and its other end held fixed to the 25 guide bar 12, the downward movement of the arms being limited by the engagement of a 30 stop pin 51 on one of them with the machine frame.

At the start of the operation of the machine, the support 20 is positioned substantially level with the top surface of the table 10. As the 20 first piece of gum delivered from the wrapping head 2 with the label applied is fed over the table 10, it passes beneath the guide rolls 44 and upon the support 20, the piece of gum being 25 accurately positioned by engagement of its advancing edge with the abutment 19. As this first piece is deposited on the support 20, the cam 32 lowers the support so that the next piece of gum is similarly fed over the table 10 and against the abutment 19, this piece thus being accurately 30 positioned over the first piece. The support 20 continues to be lowered as the other pieces of gum are similarly delivered thereto until a total of five pieces are positioned on the support as 35 shown in Fig. 5. When the five pieces have been thus stacked, the cam roll 30 rides off of the point 52 of the cam 32, whereupon the spring 34 immediately acts to elevate the support to 40 position its top surface and the underside of the lowermost piece of gum slightly above the top of the abutment 19 (Fig. 1). Suitable devices (not 45 shown) then act to carry the stack of gum off of the support and from beneath the rolls 44, and deliver them to the usual mechanism for wrapping the label about the stack to complete the package.

After the stack has been thus discharged from the support 20, the support is lowered, ready to receive the next piece of gum fed over the table 10, as above described.

50 It will be apparent that my improved gum stacking mechanism is simple in construction and positive and accurate in operation. As the pieces of gum are severally fed over and upon the support 20, as the outer lap of the newly 55 pasted label is underneath and is directed rearwardly with relation to the direction of feed of the gum, there is no danger of the seam catching and opening up or becoming deranged but to the contrary as the pieces are fed one over the other they tend by frictional engagement between them to tighten the label on the enclosing paper-lined foil wrapper and to smoothly press the overlapping edges of the label together.

60 As will be evident to those skilled in the art my invention permits various modifications without departing from the spirit thereof or the scope of the appended claims.

65 What I claim is:

1. In a gum wrapping machine of the type described having mechanism for placing a label about the individual pieces of gum from which mechanism the pieces are fed edgewise successively over a table and then arranged in stacks, the improvement which comprises a support for 70 successively receiving the pieces from the table,

means for lowering the support with relation to the table as the pieces are delivered thereto whereby the pieces are received on said support one upon the other, and means for raising said support together with a stack of gum thereon a predetermined distance with relation to the table when a predetermined number of pieces have thus been stacked thereon.

2. In a gum wrapping machine of the type described having mechanism for placing a label about the individual pieces of gum from which the pieces are fed edgewise successively over a table and then arranged in stacks, the improvement which comprises a recess in said table for successively receiving the pieces of gum thus fed over the table, a support for the pieces of gum mounted for vertical movement in said recess, means for lowering said support as the pieces are delivered into said recess whereby the pieces are received on said support one upon the other, and means for raising said support together with a stack of gum thereon when a predetermined number of pieces have thus been stacked thereon so as to discharge the stack of pieces from the recess.

3. In a gum wrapping machine of the class described, the combination of mechanism for placing labels about the individual pieces of gum comprising a rotating wrapping head, a table for successively receiving the pieces from the wrapping head, a vertically movable support for receiving the pieces from said table, means for successively feeding the pieces over the table and upon said support, means for lowering the support as the pieces are delivered thereto so as to cause the pieces to be arranged in stacked relation one upon the other on said support, and means for raising said support together with a stack of gum thereon a predetermined distance with relation to the table when a predetermined number of pieces have thus been stacked thereon.

4. In a gum wrapping machine, means for applying labels to pieces of gum, each label being wrapped about the gum with its edges overlapping and secured together, means for feeding the pieces of gum as they are thus wrapped from said labelling means to a given station, and means for stacking the pieces one upon the other at said station, and during said stacking operation causing the several pieces to be slid edgewise successively one upon the other into stacked relation with said overlapping seam of each piece disposed underneath and in a direction reverse to the direction that the overlapping edge of the seam is directed.

5. In a machine of the character set forth, a stacking mechanism comprising a support for successively receiving the gum pieces to be stacked, means for successively feeding said pieces to said support and means for lowering said support in timed relation with the feeding mechanism and retaining said support in the lowered position independently of the weight of or pressure upon the pieces reposed thereon, whereby the pieces are successively received on said support one upon the other.

6. In a machine of the character set forth, a stacking mechanism comprising a support for successively receiving the gum pieces to be stacked, means for successively feeding said pieces to said support and means for lowering said support in timed relation with the feeding mechanism, whereby the pieces are successively received on said support one upon the other, including means for raising said support a predetermined distance with relation to the table when a predetermined number of pieces have thus been stacked thereon.

mined distance when a predetermined number of pieces have been stacked thereupon.

7. In a machine of the character set forth in claim 1 wherein the means for lowering and raising the support comprises a cam for lowering the support against the tension of a spring biasing means which automatically elevates the support when released by the cam.

8. In a gum labeling machine a stacking mechanism comprising a table for successively receiving the pieces of gum to be stacked, said table comprising a stop and a part which is movable up and down, means for successively feeding said pieces one by one against said stop and upon said movable part and causing them to be stacked one upon the other to a predetermined height together with means whereby said movable part is lowered successively as the gum pieces are fed thereupon and means for elevating the movable part to a point above the level of said stop when a predetermined number of pieces of gum are fed thereto.

9. In a gum labeling and stacking machine, means for applying labels to pieces of gum with the edges of the labels overlapping and secured together, means for receiving the pieces of gum from the label applying means and stacking them one upon the other and means for transferring the labeled pieces of gum from the labeling means to the stacking means with the overlapping seam of each piece disposed underneath and advancing the pieces edgewise one by one successively upon the other into stacked relation and in a direction reverse to the direction of the overlapping edge of the seam, whereby as the pieces are slid along and stacked one upon the other the labels are tightened and the over-

lapping edges thereof are smoothly pressed together.

10. In a gum labeling and stacking machine a rotary tumbling head having slots for the reception of the pieces of gum with the labels positioned over the inner edges and two sides of the gum pieces disposed in the slots and with overlapping projecting portions of the labels disposed on the fore sides of the pieces, a table adjacent the tumbling barrel receiving the pieces of gum with the overlapping and projecting parts of the labels folded underneath and in a direction opposite to the movement of ejection as the pieces are ejected from the slots on to the table, means for sliding the pieces of gum thus disposed with the overlapping seams disposed underneath and in a direction reverse to the fold and advancing the pieces edgewise successively one by one upon the other in stacked relation.

11. In a gum labeling and stacking machine, means for applying labels to pieces of gum to provide a smooth surface and a surface with the edges of the label overlapping and secured together, aligning and stacking means for the wrapped gum, and means for successively advancing pieces of wrapped gum from the wrapping means to the aligning and stacking means, said advancing means operating to move the wrapped gum in a direction opposite to that in which the overlapping edge of the label extends and said stacking means being constructed to present the smooth surface of the wrapped gum to the overlapping surface of the succeeding piece of wrapped gum delivered by said delivery means whereby the overlapping edges are protected during delivery and stacking.

ALBERT KNEASKERN.
